TRAFFIC SIGNAL

Earl G. Maxwell, St. Louis, Mo.

Application June 13, 1952, Serial No. 20,176

Term of patent 14 years

(Cl. D72—1)

To all whom it may concern:

Be it known that I, Earl G. Maxwell, a citizen of the United States, residing in the city of St. Louis and State of Missouri, have invented a new, original, and ornamental Design for a Traffic Signal, of which the following is a specification, reference being had to the accompanying drawing, forming a part thereof.

In the drawing:

Fig. 1 is a front perspective view of a traffic signal showing my new design;

Fig. 2 is a front elevational view thereof;

Fig. 3 is a top or plan view thereof;

Fig. 4 is an end elevational view thereof, and

Fig. 5 is a rear elevational view.

The dominant features of my design are shown in solid lines.

I claim:

The ornamental design for a traffic signal, substantially as shown and described.

EARL G. MAXWELL.
